1**2,761,675****AUTOMATIC CLOTH LAYING-UP MACHINE**

Nathan Obedin, Brooklyn, N. Y.

Application November 14, 1950, Serial No. 195,553

3 Claims. (Cl. 270—31)

This invention relates to improvements in a cloth laying up machine which is automatic in its action. This invention is particularly directed to an improved drive mechanism for the fold forming or fabric folding member of such machines.

This invention is an improvement on my automatic cloth laying up machine shown in my patent application Serial No. 775,272, filed September 20, 1947, now abandoned.

In the said mechanism I have disclosed a horizontally slidable rack gear mounted lengthwise of the carriage and a pinion gear meshing with the rack gear and actuated by one of the table contacting wheels on the carriage.

An object of this invention is to secure a vertically rotatable spur gear directly on one of the stub shafts of the fold forming member, and to provide a horizontal rod slidably mounted lengthwise of the carriage and having a vertical drive bar fixed thereto, a frame vertically slidably mounted on the drive bar and having a horizontally positioned rack gear meshing with the teeth of the spur gear, the stub shaft having an extension riding in the slot, and the slot having ends forming stops for limiting the motion of the stub shaft extension and the folding member to 180 degrees.

Another object of this invention is to provide a delayed motion mechanism permitting the carriage to move a distance on the table after the stub shaft extension comes to an end of the slot, and to provide means for positively locking the folding mechanism before this additional motion takes place to prevent any motion of the fold forming member.

Another object of this invention is to provide a ratchet chain connected with the fabric folding member at a low elevation and rotatably mounted with a pawl controlled ratchet wheel at an upper elevation, the pawl being in coacting relation with the upper end of the vertical drive bar, whereby each movement of the drive bar will cause the chain to raise the fabric folding member.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of a portion of the table and the reciprocating carriage which carries the fabric folding member and the operating mechanism therefor.

Figure 2 is a side elevation of a fragmentary portion of the carriage, on an enlarged scale.

Figure 3 is a cross-sectional view taken on line 3—3 in Figure 2.

Figure 4 is a perspective view of a fragmentary portion of the fabric folding member.

Figure 5 is a front elevation of a fragmentary portion of a driving and delayed motion mechanism, drawn on an enlarged scale.

2

Figure 6 is a cross-sectional view taken on line 6—6 in Figure 5.

Figure 7 is a side elevation of the complete machine, the central portion being broken away.

Figure 8 is a top plan view showing a fragmentary portion of means of mounting a slidable frame on a rack bar.

Figure 9 is a front view of a fragmentary portion of the machine with the parts in position when the carriage is moving to the right and a transmitter shaft in contact with a stop at the end of the table.

Figure 10 is a view similar to that shown in Figure 9, with the transmitter shaft in contact with the stop at the end of the table, and a locking arm free to pass a locking bar fixed to the carriage, and an operating gear in its left-hand position.

Figure 11 is a view similar to that shown in Figures 9 and 10 with the locking arm having passed the locking bar. The operating gear is shown in its right-hand position.

Figure 12 is a view similar to that shown in Figures 9 to 11 inclusive with the carriage ready to begin its motion to the left hand side of the table.

In the illustrated embodiment of the invention, the numeral 10 indicates a cloth laying up machine which includes a table 11 on which a carriage 12 is reciprocated in any suitable manner. The carriage 12 has grooved wheels 13 which are rollable on a track 14 at one end of the table.

The carriage 12 has side walls 15 at the front end of which are vertical guide rods 16 on which bearings 17 are slidably mounted. The fabric folding member 20 is channel shaped or of U-shaped cross-section and includes two end plates 21 each having a stub shaft 22 extending therefrom. The stub shafts 22 are in alined relation and are pivotally mounted in the bearings 17.

The fabric folding member 20 comprises a back 23 and arms 24. The back includes two rollers 25 defining a slot 26 between them to guide the fabric through the folding member.

As best shown in Figure 3, one of the stub shafts 22 has an extension 28 of smaller diameter and on which a gear 29 is fixed by a screw 30. The shaft extension 28 extends beyond the outer face of the gear 29.

A horizontal rod 32 is slidably mounted lengthwise of the carriage 12 in bearings 33 secured to a side face of the carriage. The rod 32 has a vertical drive bar 34 suitably fixed thereto. The rod 32 functions as a drive bar carrier.

It is also to be noted that the guide rods 16 and the slidable bearing 17 best shown in Figures 1 and 7 are duplicated at the opposite side of the carriage 12 and that a stub shaft rotatable in the slidable bearing at the far end of the carriage, supports the far end of the fabric folding member 20 for oscillatory motion.

A frame 35 of rectangular outer form, has an upright slot 36 through which the drive bar 34 passes in frictional engagement. The frame 35 is vertically slidably mounted on the drive bar 34 (Fig. 8). The frame 35 has a horizontal slot 37 therethrough. The shaft extension 28 is frictionally rotatable in the slot 37. The frame 35 has a rack bar 38 secured thereto by screws 39 and with the teeth of the rack facing downwardly in meshed engagement with the teeth of the gear 29. Movement of carriage 12 causes rotation of the gear 29, as will be explained hereinafter.

Rotation of the gear 29 causes oscillation of the fabric folding member 20. During this rotation, the stub shaft extension 28 is slidably between the ends 40 and 41 of the slot 37. The ends of the slot 37 form stops for limiting the motion of the stub shaft extension 28.

lengthwise of the slot 37. The length of the slot limits the movement of the fabric folding member to exactly 180 degrees.

At opposite ends of the table 11 are cloth and engaging members 44, 44', each having a standard 45 upon which are pivoted suitable arms 46 carrying cross-bars 47 provided with pins 48 spaced apart so as to pass through openings 49 in one of the arms 24 respectively, of the fabric folding member 20. Each end member 44, 44' comprises stops 55'.

The end member 44 is permanently fixed to the table 11 while the end member 44' is adjustable on the table 11 to accommodate different lengths of cloth layed-up on the table.

I preferably employ two of the straight line type cloth end engaging members 44, 44' shown herewith, to secure straight line or vertical motion of the pin bar 47. Each side wall of a cloth end engaging member comprises a fixed pivot 43 upon which a link 51 is mounted.

The upper end of each link 51 carries a movable pivot 52 upon which an arm 46 is pivotally mounted. Intermediate the ends of each arm 46 is a pivot 53 which is constrained to move in a curved slot or passageway 54. The resultant motion of the free end of the pin bar 47 is vertical. The slot 54 is open at its upper end to permit the arm 46 to be swung upwardly and away from the layed up fabric on the table when it is desired to cut the layed up fabric. An arm 46' is pivoted on each standard 45 and is suitably arranged to hold the arm 46 in an upright and out of the way position, as shown in Figure 7.

The mechanism herewith also comprises what is termed a driving and delayed motion mechanism 60 (Figures 5 and 6) which includes a carrier block 58 fixed to the transmitter shaft 55 by bolts 59. The carrier block 58 overhangs the transmitter shaft 55 and extends towards the horizontal carrier rod 32. The carrier block 58 has two cam arms 69, 69' mounted on pivots 70 and having elevated roller ends 71, 71'. The cam arms 69, 69' are urged toward each other by a spring 61. As best shown in Figure 5, it will be noted that the respective arms 69 and 69' have end portions of unequal length. Also that one end portion which is substantially horizontally positioned is much longer than the other end portion which is angularly positioned. It is obvious that the elongated end portion which is substantially horizontally positioned is much heavier than the angular portion and that each arm has an inherent tendency to swing downwardly into contact with one of the rests. It is further obvious that this inherent downward motion provides the equivalent function of the spring 61, which if desired, may be dispensed with.

It is to be noted that after the fabric folding member 20 is turned to the 180 degree operating position, it is necessary to lock the said member in such position. For this locking operation, I provide an upright locking arm 85 fixed to an oscillatable support 76. The support 76 and the arm 85 are jointly pivoted on the carrier rod 32 and pressed by a spring 86 in direction of and into engagement with an end portion of a safety locking bar 87 fixed to the front face of the cam bar 73 by screws 88. The spring 86 is held in position at its outer end by a bar 89 having its ends secured by the screws 78 to the rests 75, 75', on the carrier rod 32.

Operation of invention

Assuming the fabric folding member 20 is in a 180 degree operating position, and facing rearwardly, and the locking arm 85 is in engagement with the right-hand side of the safety locking bar 87, and the carriage 12 is moved on the table 11 toward the adjustable end member 44', the following takes place. The forward end of a transmitter shaft 55 slidably mounted on the carriage 12, strikes a stop 55' on the end member 44'. This causes the transmitter shaft 55 to remain fixed, while the carriage is still moving forwardly.

For proper operation, it is required that the carriage 12 should move an additional distance of about three inches before the fabric folding member 20 is turned the full 180 degrees, when moving toward the adjustable cloth end engaging member 44'. This three inch travel is to provide the time element for the folding member 20 to make a complete 180 degree swing and so that the folding member will face the pin bar 47.

During this three inch motion, and during the 180 degree rotation of the member 20 inclined arms 63, carried by the bearings 17, pass below rollers 62 on the arms 46. This lifts the arms 46 which then slide upwardly on the upper surface of the inclined arms 63. Both arms 46 and the pin bar 47 are raised and supported so as to continue a distance between the arms 24 of the folding member 20 and then drop. The pins 48 then pass through the openings 49 in one of the arms 24, and the pins engage an end portion of the layer of cloth on the table 11, as is well known in the art. 20 The pins engage the cloth when the member 12 is moved rearwardly.

I provide the following mechanism for disengaging the locking arm 85 from the safety locking bar 87. A ball 95 is held at the free end of a stud screw 96 threaded into 25 the carrier block 58. The ball 95 is held in laterally outwardly projecting relation from the carrier block. The locking arm 85 has a laterally inwardly projecting head 98 in alignment with the ball 95. The projecting head 98 when struck by the ball 95, swings the locking arm 85 against the tension of the spring 86, so that its vertical inner surface is clear of the vertical outer surface of the locking bar 87.

It is to be noted that for the above operation, it is necessary that relative motion be provided between the 35 carrier rod 32 and the transmitted shaft 55.

At the end of the three inch movement the cam arm 69 is in engagement with the rest 75 on the carrier rod 32. The interlocked engagement of the cam arm 69 with the rest 75 causes the carrier rod 32 and the rack 40 38 to remain stationary. The movement of the carriage causes motion to be imparted to the gear 29 until the fabric folding member 20 is turned 180 degrees to face in the opposite direction.

At the end of the three inch movement, the ball 95 45 strikes the inwardly projecting head 98 on the locking arm 85 and moves the locking arm 85 out of engagement with the right hand side of the safety locking bar 87. This permits the locking bar 87 to move with the carriage until the fabric folding member 20 is in the reversed 50 operating position. This takes place at each end of the carriage movement and only when a locking arm 85 fixed to the horizontal rod 32 is free to pass the safety locking bar 87. This motion takes place only when a transmitter shaft 55 is fixed relative to the rod 32, as shown 55 in Figures 6, 9 and 10.

It is to be noted that on the reverse of the carriage to the left, the transmitter shaft 55 strikes the left hand cloth engaging member 44. The cam arm 69' comes into engagement with the rest 75'. Simultaneously, the ball 95 60 engages the locking arm 85 and moves it laterally out of engagement with the locking bar 87. This disengagement allows the carrier rod 32 to start its right-hand motion for rotation of the folding member and also carrying the locking arm 85 to the right-hand engaging end of the bar 87. At the end of the rotation of the folding member, due to the right-hand motion of the rod 32, the roller end 71' of the arm 69' engages the right-hand cam 72, thus disengaging the arm 69' from the rest 75' and the rod 32 then ceases motion. During the right-hand movement of the carriage, the rod 32 moves to the left in relation to the carriage and the locking arm 85 is carried to the left engaging end of the safety locking bar 87. Further motion of the carriage 12 will move the ball 95 out of contact with the laterally inwardly projecting head 98 and this permits the tension of the spring 75

86 to cause the locking arm 85 to engage the left hand side of the safety locking bar 87 and this locks the fabric folding member 20 in said position, because the locking bar 87 prevents the locking arm 85 and the rod 32 from making any movement.

It will be noted that I have provided safety stops 99, 99' fixed to the carrier rod 32 and which are engaged by the cam arms 69, 69' at the completion of the carriage movement. This brings the machine in position for reverse movement.

The carriage is then moved in the opposite direction and all the said movements are reversed.

In operation, as the cloth is laid up on the table, the drive bar 34 contacts a pawl carrier 100 pivotally mounted on a shaft 101. The carrier 100 supports a pawl 102 pivotally mounted on pin 103. The upper end of the pawl 102 is tooth shaped and normally meshes with one of the teeth of a ratchet wheel 104 fixed to the shaft 101.

A sprocket chain 105 is in engagement with a sprocket gear 106 fixed to the shaft 101. One end of the sprocket chain 105 is fixed to the upper end portion of a bearing 17. The other end of the sprocket chain 105 passes around a guide pulley (not shown) and is fixed to the lower end portion of the bearing 17. As the sprocket gear 104 is actuated due to the reciprocating movements of the drive bar 34, the sprocket chain 105 is actuated and raises the bearings 17. The fabric folding member 20 is thus raised in step-by-step relation from the table 11.

At the extreme upper right-hand corner of Figure 1 is a tooth selector 110 which cooperates with the pawl carrier 100 in determining the number of teeth to be moved during each right hand motion of the carriage 12. During the left hand movements of the carriage 12, when the bar 32 moves to the right, the freely swinging carrier 100 swings counterclockwise till it engages the selector 110. The drive bar 34 does not pass beneath the carrier 100 but only actuates it slightly.

It is to be noted that, in operation when the carriage 12 is moving to the right, the relative positions of the cams 72 and 80 in Figures 9 to 12 inclusive are as follows:

In Figure 9, the roller 71' and cam 72 are out of contact. There is relative motion between the rod 32 and transmitter shaft 55.

In Figure 10, the roller 71' and the cam 72 are in contact. The arms 69 and 69' are in contact with the rests 75 and 75'.

In Figure 11, the roller 71' and the cam 72 are disengaged. The roller 71 and cam 80 are in engagement. As a result the arms 69 and 69' are ready for disengagement from the stops 75 and 75' and this causes relative motion again between the rod 32 and the transmitter shaft 55.

In Figure 12, the roller 71 and the cam 80 are in disengagement. The arms 69 and 69' remain in disengagement with the stops 75 and 75'. As a result there is relative motion between the rod 32 and the transmitter shaft 55.

It is to be noted that repetition of the above cycle, with the carriage 12 moving to the left, the gear 29 will be caused to rotate only when there is no relative motion between the rod 32 and the transmitter shaft 55.

The relative positions of the rod 32 and the transmitter shaft 55 in Figures 9 to 12 inclusive are as follows when moving the carriage to the right:

In Figure 9, the shaft 55 strikes the stop 55'. The rod 32 continues to move with the carriage 12. The locking arm 85 and the ball 95 are in spaced apart relation. Locking arm 85 and locking bar 87 move as a unit.

In Figure 10, the transmitter shaft 55 is fixed. Rod 32 continues to move with the carriage 12. The locking arm 85 and the ball 95 are in alignment. As a result, the locking arm 85 is being disengaged from the locking bar 87.

In Figure 11, the shaft 55 and the rod 32 are fixed. The locking arm 85 and the ball 95 remain in alignment.

The locking arm 85 has moved to the left of the locking bar 87 while the carriage 12 continues to move to the right. Gear 29 has rotated.

In Figure 12, the shaft 55 remains fixed against the stop 55'. The rod 32 moves with the carriage 12. The locking arm 85 is out of alignment with the ball 95.

The disclosure in Figures 9 to 12 inclusive shows the cooperation between the cams 72 and 80 and between rod 32 and transmitter shaft 55. This disclosure also shows how the gear 29 is rotated during each cycle.

In accordance with the patent statutes I have described and illustrated the preferred embodiment of my invention, but it will be understood that various changes and modifications can be made therein without departing from the spirit of the invention as defined by the appended claims.

I claim:

1. In combination with a fabric laying-up machine comprising a table, a carriage reciprocable on said table said carriage having vertical guide means, bearings movably mounted on said guide means, a fabric folding member having stub shafts and being pivotally mounted on said stub shafts in said bearings, cam bars on said carriage, each cam bar having a bevelled cam surface, a horizontal cam actuated rod slidably mounted lengthwise of said carriage, and having a vertical drive bar fixed thereto at its front end and two rests at its rear end, a delayed motion mechanism on said carriage and comprising a transmitter shaft, a carrier block fixed to said transmitter shaft and having two arms pivotally mounted thereon, each arm having one end engageable with one of said cam surfaces and the other end engageable with one of said rests, a frame vertically slidably mounted on said drive bar and having a horizontal slot therethrough and a horizontally positioned rack, a gear secured to one of said stub shafts and meshing with the teeth of said rack, said stub shaft having a portion extending beyond the outer face of said gear, said shaft extension riding in said slot, said slot having ends forming stops for limiting the motion of said stub shaft extension and said folding member to 180 degrees, said arms having end portions of unequal length, whereby one end portion of each arm is inherently movable into contacting relation with one of said rests, a stop on said table in the path of movement of said transmitter shaft to bring said shaft to a state of rest, further movement of said carriage causing one of said arms to swing into engagement with one of said rests on said cam actuated rod, further movement of said carriage causing movement of said gear and rotation of said fabric folding member to said 180 degree position, a spring tensioned pawl pivoted on said cam rod for locking said folding member in said turned position and for locking said cam rod to said carriage, and means acting on return motion of said carriage for releasing said pawl to permit reverse motions of said mechanisms in the opposite direction.

2. In combination with a fabric laying-up machine comprising a table, a carriage reciprocable on said table, said carriage having vertical guide rods, bearings movably mounted on said guide rods, a fabric folding member having stub shafts and being pivotally mounted on said stub shafts in said bearings, cam bars on said carriage, each cam bar having a bevelled cam surface, a horizontal cam actuated rod slidably mounted lengthwise of said carriage, and having a vertical drive bar fixed thereto at its front end and two rests at its rear end, a delayed motion mechanism on said carriage and comprising a transmitter shaft, a carrier block fixed to said transmitter shaft and having two arms pivotally mounted thereon, each arm having one end engageable with one of said cam surfaces and the other end engageable with one of said rests, a frame vertically slidably mounted on said drive bar and having a horizontal slot therethrough and a horizontally positioned rack, a gear secured to one

of said stub shafts and meshing with the teeth of said rack, said stub shaft having a portion extending beyond the outer face of said gear, said shaft extension riding in said slot, said slot having ends forming stops for limiting the motion of said stub shaft extension and said folding member to 180 degrees, said arms being spring-tensioned toward each other, a stop on said table in the path of movement of said transmitter shaft to bring said shaft to a state of rest, further movement of said carriage causing one of said arms to swing into engagement with one of said rests on said cam actuated rod, further movement of said carriage causing movement of said gear and rotation of said fabric folding member to said 180 degree position, a spring tensioned pawl pivoted on said cam rod for locking said folding member in said turned position and for locking said cam rod to said carriage, and means acting on return motion of said carriage for releasing said pawl to permit reverse motions of said mechanisms in the opposite direction.

3. In combination with a fabric-laying up machine, comprising a table, a carriage reciprocable on said table, said carriage having vertical guide rods, bearings movably mounted on said guide rods, a fabric folding member having stub shafts and being pivotally mounted on said stub shafts in said bearings, cam bars on said carriage, each cam bar having a bevelled cam surface, a horizontal cam actuated rod slidably mounted lengthwise of said carriage, and having a vertical drive bar fixed thereto at its front end and two rests at its rear end, a delayed motion mechanism on said carriage and comprising a transmitter shaft, a carrier block fixed to said transmitter shaft and having two cam arms pivotally mounted thereon, each arm having one end engageable

5 with one of said cam surfaces and the other end engageable with one of said rests, a frame vertically slidably mounted on said drive bar and having a horizontal slot therethrough and a horizontally positioned rack bar, a gear secured to one of said stub shafts and meshing with the teeth of said rack bar, said stub shaft having a portion extending beyond the outer face of said gear, said shaft extension riding in said slot, said slot having ends forming stops for limiting the motion of said stub shaft extension and said folding member to 180 degrees, said cam arms being spring-tensioned toward each other, movement of said carriage causing a stop on said table to bring said shaft to a state of rest, further movement of said carriage causing one of said cam arms to swing into engagement with one of said rests on said cam actuated carrier rod, further movement of said carriage causing movement of said gear and rotation of said fabric folding member to said 180 degree position, a spring tensioned locking arm pivoted on said carrier rod for locking said folding member in said turned position and for locking said carrier rod to said carriage, and means acting on return motion of said carriage for releasing said locking arm to permit reverse motions of said mechanisms in the 10 15 20 25 opposite direction.
